Primary Examiner — Kendra Leslie Hamilton(57) **CLAIM**

I claim the ornamental design for tether for animals, as shown and described.

DESCRIPTION

1.1 is a left side view of a tether for animals showing my new design;

1.2 is a right side view thereof;

1.3 is a front view thereof;

1.4 is a rear view thereof;

1.5 is a top plan view thereof;

1.6 is a bottom plan view thereof; and,

1.7 is a front perspective view thereof.

The broken lines in the drawings depict portions of the tether for animals that form no part of the claimed design.
